PAPER SLITTER

David R. McKinley and Peter J. Van Norden,
Kalamazoo, Mich.

Application June 12, 1939, Serial No. 278,602

6 Claims. (Cl. 164—60)

This invention relates to paper slitters and has for its objects:

First, to produce a new and improved paper slitter.

Second, to produce such a slitter in which the bearing and other working parts, exclusive of the knife, are protected against the lint and the like which collect on machinery of this type.

Third, to produce such a slitter in which the knives are held resiliently in cooperating position and in which the knives may be separated for the purposes of adjustment and sharpening by an axial movement and in which one of the knives may, by a simple manipulation, be retracted from the other knife away from the plane of the paper on which the knives are working to facilitate removal of the blades for sharpening and the adjustment of the device.

Other objects and advantages pertaining to details and economies of construction and operation will appear from the description to follow. The invention is defined in the claims. A preferred embodiment of my invention is illustrated in the accompanying drawing, in which:

Fig. 1 is a view partly in section of our improved slitter bringing the knives in cooperating cutting position, taken on line 1—1 of Figs. 2 and 4.

Fig. 2 is a detail sectional view taken on line 2—2 of Fig. 1.

Fig. 3 is a view similar to that of Fig. 1 showing the knives separated for the purposes of adjustment.

Fig. 4 is a view of the rear of the supporting casing taken from the right of Figs. 1 and 2.

In our improved device are provided the rotary cutting knives 1 and 2 disposed to sever a web of paper 3 which is fed thereto. The knife 2 is adjustably supported by means of a support 4 having column 5 slidably supported in the supporting block 6. The support 4 is provided with a cylindrical bore 7 in which is disposed a cylindrical member 8 which is both slidable and rotatable in the bore 7. The cylindrical member 8 carries the axle 9 for the knife 2. The axle is suitably supported in ball bearings 10 and 11 mounted on the cylindrical member and extends axially of the cylindrical member 8 but is eccentrically disposed with respect to the axis of the cylindrical member 8 and of the bore 7. On the axis is a suitable blade holder 12 with nut 13 for clamping the blade 2. The axle 9 extends from the end 14 of the bore 7. The end 15 of the bore 7 is closed by a suitable cap 16 held in place by

19 is fixed to the cylindrical member 8 and extends through the aperture 18.

To the stem 19 is fixed a ring handle 20 which may be used for moving the cylindrical member 8 axially of the bore 7 or for rotating it therein. 5 The handle 20 is provided with an aperture 21 to be engaged by a suitable hook and is provided with a pin 22 spring pressed by a spring 23 in a bore 24 in the handle to engage recesses 25, 26 and 27 in the cap 16. A compression 10 spring 28 is mounted in the bore 7 and engages the cylindrical member 8, urging it to the left of Fig. 1 to hold the knives 1 and 2 in resilient operating engagement. One end of the spring bears against the cap 16. The support 4 and the 15 cylindrical member 8 are connected by a pin and slot connection indicated at 29. The pin 30 extends from the support to engage the slot 31 in the cylindrical member 8. This slot is provided with a portion 32 extending in a direction axial 20 of the bore to lock the cylindrical member against rotation when the knives are in operative engagement, and a portion 33 extending circumferentially and connected with the portion 32 serving 25 to hold the knives out of engagement when the cylindrical member 8 is moved to the right in Fig. 1 and is then rotated to move the knife 2 upwardly as viewed in Fig. 1 away from the paper and the knife 1.

In Fig. 1, we show the knives in cutting engagement. In Fig. 3, we show the knives separated axially and also with the knife 2 moved away from the plane of the paper. This is accomplished by pulling on the handle 20 to retract the cylindrical member 8 in the bore 7 and by then turning the handle 20 in a counterclockwise direction so that the pin 30 will engage in the portion 33 of the slot 31 to hold the blades in axially separated position while the eccentric mounting of the axle 9 and the turning of the 35 cylindrical member raise the blade 2 to the position shown.

It will be apparent that when the blade 2 has been moved to the position shown in Fig. 3, it is possible to easily remove the blade 2 for sharpening and it is possible also to adjust the blades to the desired relative position before moving the blade 2 down so that it will meet blade 1 and then permitting it to move axially to resilient engagement with the blade. This device is particularly 45 useful because of the ease of adjustment and because it is possible by merely reaching in with a hook to move the blade from the position of Fig. 1 to the position of Fig. 3, and because when the blades are in operating position they are held 50 55

resiliently in engagement. It will be apparent that the working parts are well protected against accumulation of lint which interferes with the operation of slitters in general.

5. If it is desired, the slot 31 may be provided with an extension 34 by means of which the blade 2 may be held away from the blade 1 without materially raising the blade away from the plane of the paper to be cut.

10. Having thus described our invention, what we claim as new and desire to secure by Letters Patent is:

1. In an apparatus of the class described, the combination of a knife, a second knife in cooperative relation thereto and having a support having a cylindrical bore therein, a cylindrical member rotatably and slidably mounted in said bore, an axle for said second knife eccentrically mounted on and parallel to the axis of said cylindrical member and extending from one end of said bore whereby on rotation of said cylindrical member said knives may be moved out of axial register, a closure for the other end of said bore, a spring in said bore urging said cylindrical member axially of said bore to force said second knife resiliently into operative relationship with said first mentioned knife, a pin and slot connection between said cylindrical member and said support including a slot having a portion extending along said bore to lock said cylindrical member against rotation when the knives are in cutting relationship, a connected portion extending circumferentially of the bore to lock said cylindrical member against axial movement in said bore when it has been retracted to separate said knives and when it is rotated, and means on said cylindrical member extending from said bore for retracting said cylindrical member and for rotating it.

40. 2. In an apparatus of the class described, the combination of a knife, a second knife in cooperative relation thereto and having a support having a cylindrical bore therein, a cylindrical member rotatably and slidably mounted in said bore, an axle for said second knife eccentrically mounted on and parallel to the axis of said cylindrical member and extending from one end of said bore whereby on rotation of said cylindrical member said knives may be moved out of axial register, a closure for the other end of said bore, a spring in said bore urging said cylindrical member axially of said bore to force said second knife resiliently into operative relationship with said first mentioned knife, and means on said cylindrical member extending from said bore for retracting said cylindrical member and for rotating it.

60. 3. In an apparatus of the class described, the combination of a knife, a second knife in cooperative relation thereto and having a support having a cylindrical bore therein, a cylindrical member rotatably and slidably mounted in said bore, an axle for said second knife eccentrically mounted on and parallel to the axis of said cylindrical member whereby on rotation of said cylindrical member said knives may be moved out of axial register, a spring in said bore urging said cylindrical member axially of said bore to force said second knife resiliently into operative relationship with said first mentioned knife, and means on said cylindrical member extending from said bore for retracting said cylindrical member and for rotating it.

5. cylindrical member axially of said bore to force said second knife resiliently into operative relationship with said first mentioned knife, and means on said cylindrical member extending from said bore for retracting said cylindrical member and for rotating it.

4. In an apparatus of the class described, the combination of a knife, a second knife in cooperative relation thereto and having a support having a cylindrical bore therein, a cylindrical member rotatably and slidably mounted in said bore, an axle for said second knife eccentrically mounted on and parallel to the axis of said cylindrical member whereby on rotation of said cylindrical member said knives may be moved out of axial register, a spring in said bore urging said cylindrical member axially of said bore to force said second knife resiliently into operative relationship with said first mentioned knife, a pin and slot connection between said cylindrical member and said support including a slot having a portion extending along said bore to lock said cylindrical member against rotation when the knives are in cutting relationship, a connected portion extending circumferentially of the bore to lock said cylindrical member against axial movement in said bore when it has been retracted to separate said knives and when it is rotated, and means on said cylindrical member extending from said bore for retracting said cylindrical member and for rotating it.

5. In an apparatus of the class described, the combination of a knife, a second knife in cooperative relation thereto and having a support comprising axially movable rotary means and an axle for said second knife eccentrically mounted on said rotary means and parallel to the axis thereof, resilient means bearing on said rotary means to resiliently urge said rotary means axially to resiliently hold said knives in cooperative relationship, and means for retracting said rotary means axially against the force of said resilient means to separate said knives and for rotating said rotary means to separate said knives by the eccentric movement of the axis for said second knife when the knives have been separated by the axial retraction of said rotary means, and means for holding said rotary means in retracted position.

6. In an apparatus of the class described, the combination of a knife, a second knife in cooperative relation thereto and having a support comprising axially movable rotary means and an axle for said second knife eccentrically mounted on said rotary means and parallel to the axis thereof, resilient means bearing on said rotary means to resiliently urge said rotary means axially to resiliently hold said knives in cooperative relationship, and means for retracting said rotary means axially against the force of said resilient means to separate said knives and for rotating said rotary means to separate said knives by the eccentric movement of the axis for said second knife when the knives have been separated by the axial retraction of said rotary means.
